DESIGN FOR A DOOR WICKET

Allen Bloom, New York, N. Y.

Application October 15, 1947, Serial No. 141,902

Term of patent 7 years

(Cl. D10—7)

To all whom it may concern:

Be it known that I, Allen Bloom, a citizen of the United States and a resident of the city of New York, in the county of Queens and the State of New York, have invented a new, original, and ornamental Design for a Door Wicket, of which the following is the specification, reference being had to the accompanying drawing, forming part thereof.

I claim:

The ornamental design for a door wicket, substantially as shown and described.

ALLEN BLOOM.
